UNITED STATES PATENT OFFICE

GLEN M. ARON, OF ALHAMBRA, CALIFORNIA, ASSIGNOR TO MORRIS B. PENDLETON,
OF SAN GABRIEL, CALIFORNIA

LIQUID-SAMPLING DEVICE

Application filed February 21, 1928. Serial No. 255,928.

My invention relates to the art of sampling liquid, being more particularly a device or apparatus by means of which a true and accurate sample of the liquid contents of a tank may be taken.

Petroleum oils, after production, are stored in large tanks of many thousand barrels' capacity and the contents thereof sold according to the gravity of the oil, so that it is extremely important to obtain uniform samples of the oil in the tank which will accurately disclose the nature of the whole body of oil in the tank, and it is one of the principal objects of my invention to produce a sampling device of the character described, by means of which a uniform sample of the oil in the tank in a continuous vertical column may be taken.

It is a further object of my invention to provide means whereby a sampling device of the character described may be readily assembled and installed on any of the common forms of tanks now in use for the storage of oils and similar liquids.

Another object of my invention is to provide a device of the character described and means of mounting the same on a tank whereby the sampling device adjusts itself to a true vertical position in the tank.

Other objects and advantages will appear hereinafter from the following description and accompanying drawings.

Referring to the drawings, which are for illustrative purposes only,

Fig. 1 is a vertical sectional view of a portion of a tank, showing a sampling device embodying a form of my invention mounted thereon.

Fig. 2 is an elevational view in the direction of the arrow 2 of Fig. 1.

Fig. 3 is an enlarged vertical sectional view showing the upper part of my invention as illustrated in Fig. 1.

Fig. 4 is an enlarged outside view in the direction of arrow 4, Fig. 3.

Fig. 5 is an enlarged sectional plan view on line 5—5 of Fig. 1.

Fig. 6 is an enlarged sectional plan view on line 6—6 of Fig. 1.

Fig. 6^a is a sectional view corresponding

to Fig. 6, showing the relative parts in angular adjustment.

Fig. 7 is an enlarged sectional view along the line 7—7 of Fig. 1.

Fig. 7^a is a view similar to Fig. 7 showing the parts in a different relative position.

Fig. 8 is an enlarged sectional view along the line 8—8 of Fig. 1.

Fig. 8^a is a sectional view corresponding to Fig. 8, showing relative parts in angular adjustment.

Fig. 9 is a sectional view along the line 9—9 of Fig. 8.

Referring more particularly to the form of my invention shown in the accompanying drawings, 11 designates the bottom of the tank, 12 the side wall, 13 the roof, and 14 a hole in the roof which is adapted to receive the sampling device generally indicated at

15. Mounted above the mentioned opening 14, I provide a seat member 16 which comprises an annular flanged base 17 adapted to surround the hole 14 and to be retained upon the roof 13 by means such as the bolts 18.

Upwardly mounted on the mentioned flange 17, by means of welding or in any other suitable manner, I provide a conical seat support 19 having a circular seat 20 formed in the upper end thereof. The seat 20 is arranged

to receive the semi-spherical bottom 21 of a collar or shoulder 22 which is in threaded engagement with an outside tube 23 of the sampling device. The conical seat support 19 is adapted to be of sufficient height to elevate the seat 20 and collar 21 above the top of the tank at a distance which will permit the use of this device upon a tank roof having water or other liquid thereon, such as the commonly used liquid sealed roofs. It will be understood that the semi-spherical seat portion will permit the vertical alignment of the tube 23, irrespective of the angle at which the seat is mounted upon the tank roof.

The lower end of the tube 23 is threaded into a fitting 24 provided with a screw plug 24' and an outlet pipe 25, which outlet pipe is connected by means of a flexible hose or pipe 26 with a discharge pipe 27 extending through an opening 28 in the side wall of the tank and through a gland 29 in a handhole

90

95

100

cover or plate 30, secured to the tank by means of suitable bolts 31. The discharge of liquid through the pipe 27 is controlled by means of a suitable valve or cock 32.

5 Rotatably mounted within the outer tube 23 is an inner tube 40, such inner tube 40 being downwardly supported by the screw plug 24', and extending from the fitting 24 upwardly through the outer tube extending 10 thereabove to receive a spool or shieve 41 secured in any suitable manner, such as set screws 42, to the tube 40, and providing means for the reception of a flexible member, such as the cable 43, which is secured thereon by 15 means such as a screw 44 and by means of which the inner tube may be rotated. The upper end of the inner tube is closed by a plug 45, and the lower end of the interior of the inner tube is rendered flush with the 20 bottom of the opening in outlet fitting 24, by means of an upwardly extending frusto-conical projection 24'' formed upon the plug 24'. The outer tube 23 is provided with a series of longitudinal slots 46, disposed 25 throughout its length, such slots being alternately arranged on opposite sides of the tube in such a manner as to provide for the entrance of liquid into the tube throughout the tube from a point indicated by the dot and 30 dash line A in Fig. 1, to a point of highest liquid level in the tank substantially just below the roof of the tank.

The inner tube 40 is similarly slotted with 35 a series of slots 48, disposed on opposite sides of such tube and arranged to correspond with the slots in the outer tube. The outer, and inner tubes, 23 and 40 respectively, are provided with vent openings 49 and 50 above the tank roof for the purpose of allowing the 40 entrance of air through the tubes when the valve 32 is open, the outer tube opening 49 being shown as co-operating with an opening 49' formed in the collar 22, as is best illustrated in Figs. 6 and 6^a. Provision is 45 also made for preventing the rotation of the outer tube in the collar 22, which consists of a bolt or set screw 51 extending into the collar and engaging the upper threaded end of the outer tube 23, and, in order that the 50 rotatable movement of the inner tube in the outer tube may be limited between slot opening and slot closing positions, I provide the lower surface of the spool 41 with a downwardly extending lug or pin 53, which is engageable with upwardly extending lugs 54 and 55, mounted on the upper face of the collar 22. The lugs 54 and 55 are so mounted that the radial distance between 55 their engaging faces is substantially 90°.

Means are provided for mounting the cable or rope 43 upon the tank in a manner such that it is conveniently accessible to the operator, which means comprise a pair of pulleys 57 and 57', over which opposite ends

of the cable 43 extend, the pulleys being mounted on a shaft 59, supported by the legs 60 and 62 that engage an edge 62' of the tank top 13. The shaft 59 is supported against lateral displacement by means of the arm 63 which is mounted upon an extending ear 65 by means of a bolt 66, the ear 65 being formed on the seat support 16. Sleeve members 67 and 68 prevent the inward movement of the pulleys 57 and 57', and the respective parts 75 are held in relative adjustment upon the shaft 59 by means such as the nuts 69 and 69' which engage the threaded opposite ends of the shaft. It will be understood that it is the purpose of this pulley construction 80 to make the sampling device independent of any unnecessary attachments to the tank roof, the fixed support being from the seat supporting member, and the legs 60-62 being independent of any special roof construction. 85

In order that the cable 43 may always be conveniently accessible to the operator, and, further, for the purpose of preventing twisting and accidental catching on moving objects near the tank, I provide a retaining pulley 71, which is mounted on the side 12 of the tank, near the outlet valve 32, by means such as the arm 72 and the bolt 73. The arm 72 I show as being mounted upon the handhole cover 30 by means of the bolts 31. 90

In operation, it is understood that the inner tube is rotated to a position in which the slots in the inner and outer tubes are out 100 of register, as shown in Figs. 7^a and 8^a, until such time as it is desired to take a sample of the liquid contents of the tank, whereupon the inner tube is rotated through the medium of the cable or rope, as heretofore described, so that the slots in the inner tube 105 register, as shown in Figs. 7 and 8, it being understood from drawings, particularly Figs. 1, 8^a and 9, that the lowermost slot 75 in the tube 40 registers an aperture 48' in the tube 23 and a slot 80 formed in the fitting 24. The fitting 24 is further provided with an outer slot 81 which cooperates with the bottom slot 46' in tube 23. 110

115 It will be understood that when all of the slots throughout the tubes are in register, as just described, a sample received in the inner tube is a continuous one from the top of the upper most slot to the bottom of the lowermost slot in the tubes, admitting a column or core of oil into the sampler. The inner tube is then rotated so that the slots in the inner and outer tubes are out of register, the lowermost slot 80 in the inner tube 120 registering with the outlet pipe 25, at which point in the operation, the inner tube contains a sample taken as just described. This sample may be drawn off through the valve 125 130

32 by opening the same into any receptacle for receiving such sample.

With respect to the vent openings 49, 49' and 50, such openings are out of register when the slots 46 and 48 in the tubes are in register so that when the sampler is allowed to stand open, that is, the slots 46 and 48 in register, there is no leakage of gas through the sampler. This is of great importance as gas leakage increases fire hazard and consequently should be avoided. However, during the operation of filling the sampler some of the top slots which are above the liquid level function as air outlets while the passages 49, 49' and 50 admit air during the draining of the sample column.

It will be understood that, if desired, the slots in the inner and outer tubes may be in register during the tank filling operation and the sample taken, as above described.

It will be further understood that any accumulation of oil in the pipe 25 should be drawn off prior to the turning of the inner tube, to bring the outlet slot therein in register with the outlet pipe. This is done by opening the valve 32, since if the mentioned accumulation of oil in the pipe 25 were permitted to mingle with the sample, a true sample would not be received.

I claim as my invention:

1. In combination with a tank, a fluid sampling device comprising tubular sample receiving means and means for suspending said sample receiving means on the tank roof, said suspending means consisting of a spherical seat mounted on the tank and a cooperating shoulder on said tubular means engaging said seat.

2. In combination with a tank, a fluid sampling device comprising tubular sample receiving means and means for suspending said sample receiving means on the tank roof, and means at the lower end of said tubular means including a flexible tubular member extending through the wall of the tank for withdrawing fluid from the tubular means.

3. In combination with a tank, a fluid sampling device comprising tubular sample receiving means and means for suspending said sample receiving means on the tank roof, said sample receiving means consisting of an outer stationary tube having openings therein and an inner rotatable tube having openings therein arranged to register with the openings in the outer tube, the openings in both the inner and outer tube being arranged in staggered relation with one another and forming when the opening in said tubes are coincident, fluid receiving passages which established communication through the tubes throughout the entire distance between the top and bottom openings.

4. In combination with a tank, a fluid sampling device comprising tubular sample receiving means and means for suspending

said sample receiving means on the tank roof, said sample receiving means consisting of an outer stationary tube having openings therein and an inner rotatable tube having openings therein arranged to register with the openings in the outer tube, and means for rotating the inner tube, said rotating means consisting of a spool on said inner tube, a cable on said spool, and rotatable means for supporting said cable over the edge of the tank.

5. For use with a tank having a roof and a fluid sampling device suspended thereon; means for suspending said sampling device from the tank roof, said means including a spherical seat adapted to be mounted upon said roof; and a cooperating spherically formed shoulder on said sampling device seat-ing in said spherical seat.

6. In combination with a tank, a fluid sampling device comprising: tubular sample receiving means; means for supporting said sample receiving means in a tank; and means comprising a non-rigid connection at the lower end of said tubular means and extending through the wall of the tank for withdrawing fluid from the tubular means.

7. In combination with a tank, a fluid sampling device embodying: tubular sample receiving means and means for supporting said sample receiving means in a tank, said sample receiving means consisting of an outer tube having openings therein and an inner tube having openings therein arranged to register with the openings in the outer tube; and means including a member extending downwardly along the side of the tank for rotating one of said tubes.

In testimony whereof, I have hereunto set my hand at Los Angeles, California, this 15th day of February, 1928.

GLEN M. ARON.
